UNITED STATES PATENT OFFICE.

DANIEL C. RIPLEY, OF PITTSBURG, PENNSYLVANIA, ASSIGNOR TO THE
UNITED STATES GLASS COMPANY, OF SAME PLACE.

DESIGN FOR A GLASS VESSEL.

SPECIFICATION forming part of Design No. 27,288, dated July 6, 1897.

Application filed May 29, 1897. Serial No. 638,813. Term of patent 3½ years.

To all whom it may concern:

Be it known that I, DANIEL C. RIPLEY, of Pittsburg, in the county of Allegheny and State of Pennsylvania, have invented a new 5 Design for Glass Vessels, of which the following is a full, clear, and exact description, reference being had to the accompanying drawings, forming part of this specification, in which—

10 Figure 1 shows in top plan view a glass vessel embodying my design. Fig. 2 is a bottom plan view thereof, and Fig. 3 is a vertical section on the line III III of Fig. 1.

My design consists in a glass vessel of the 15 shape and configuration substantially as herein described, and shown in the accompanying drawings.

In the drawings, 2 represents the body of the vessel, which is of oblong curved form, having slightly-flaring sides 3 and a bottom 20 4, which on the interior is formed with a sunken figure 5, the outside of the bottom being substantially plain.

I claim—

The design for a glass vessel substantially 25 as herein shown and described.

In testimony whereof I have hereunto set my hand.

DANIEL C. RIPLEY.
